W. L. IMLAY.
Apparatus for Separating Ores.
No. 228,719. Patented June 8, 1880.

INVENTOR.

UNITED STATES PATENT OFFICE.

WILLIAM L. IMLAY, OF CAMDEN, NEW JERSEY.

APPARATUS FOR SEPARATING ORES.

SPECIFICATION forming part of Letters Patent No. 228,719, dated June 8, 1880.

Application filed November 8, 1877.

To all whom it may concern:

Be it known that I, WILLIAM L. IMLAY, of Camden, in the county of Camden and State of New Jersey, have invented a certain new and useful Improvement in Apparatus for Separating Ores; and I do hereby declare the following to be a full, clear, and exact description of the invention, such as will enable others skilled in the art to which it pertains to make and use it, reference being had to the accompanying drawings, which form part of this specification, in which—

Figure 1 is a vertical longitudinal section. Fig. 2 is a side elevation. Figs. 3 and 4 are plans of details.

My invention has relation to an improved machine or apparatus for separating ores, in which separation is effected by agitating the ores in a peculiar manner, while at the same time a current or stream of water is caused to play upon them; and said machine or apparatus consists of a suitable frame-work supporting a tray or series of trays arranged in a slanting position and connected with an eccentric or crank shaft or shafts in such manner that a reciprocating motion lengthwise and an elliptical motion will be communicated to said tray or trays. Said tray is provided with a water-box of peculiar construction, arranged to discharge its liquid contents upon the ore fed to the tray, the effect of the combined action, resulting from the movement of the actuating-shaft and the play of the water, being to cause the sand or earthy matter to work down to and over one end of said tray, while the mineral or metal separated therefrom works to the other end of the tray, and is there collected or caused to be discharged by means of a chute or incline into a receiver, the operation being continuous—*i. e.*, proceeding without intermission for charging or discharging so long as the feed is kept up.

Referring to the accompanying drawings, A designates the frame of the machine or apparatus, consisting of a base, A', having four posts or uprights, a a, with longitudinal bars a' a', connecting said posts at the top, as shown. a' a' are other bars, firmly fastened to the inner sides of the posts a a, forming horizontal ways.

B represents a tray, of which any desired

number may be employed, as hereinafter set forth. Said tray is of the elongated form shown, having a flat bottom, b, sides b' b', and ends b² b³. A short distance from each end, 55 and resting on the bottom b, are transverse cleats or ribs C C', which form dams, the sides of which adjacent to the water-box are inclined, while their reverse sides are vertical. Between the dam C and the end b² the bottom 60 b is formed with perforations b⁴, which open into a conduit or trunk, E, and between the dam C³ and the end b³, said bottom is cut away, as shown at b⁵, forming an opening to another trunk or conduit, D. Covering the perforations b⁴, and extending from a point above the dam C to the end b² of the tray, supported by and between the sides of the tray, or in any other suitable way, is a removable incline, C². Between the lower edge of said incline and the 70 upper surface of the dam C there is a passage-way, C³, for a purpose hereinafter set forth.

The tray B rests on an oblong rectangular frame, F, composed of the side bars, f f, and end bars, f' f', and is firmly secured to said frame by side pieces, f², or other equivalent means, so that said frame forms a component of said tray.

G is an eccentric or crank shaft journaled 80 in suitable bearings g g on the bars a², and attached, by means of boxes g' g, to the frame F, so that when said shaft is rotated said frame and the tray resting upon and secured to it will be caused to move longitudinally through 85 their entire length and to describe or move through an ellipse between their point of connection with said shaft and their support at the opposite end.

The end of the frame F remote from the 90 shaft G is sustained upon a cross-piece, F', which rests upon the bars a², said cross-piece being of such thickness that the tray B will be slightly elevated at the end adjacent to said cross-piece, or will be horizontal throughout 95 when the shaft or eccentric of the shaft G is at its top center.

H is a box composed of two wedge-shaped or tapering ends, h h, and two inclined or flaring sides, h' h'. The sides h' h' are arranged 100 to almost meet at their lower edges, so as to leave a narrow opening, h², between them, or

they may be slightly farther apart than the breadth indicated for said opening, and be connected by a perforated metallic plate, h^3 , which forms a bottom for said box. The box 5 H is pivoted between the sides $b' b'$ of the tray, as shown at h^4 , and is provided with a notched lever, I, engaging with a stud or pin, i, in the end b^2 of the tray B.

K is a pipe or inlet for the admission of water to the box H. A hopper, apron, or other device for feeding ore to the tray B between the water-box and the end b^2 , or upon the incline C^2 , should be also provided.

The operation is substantially as follows:

10 15 The ore or sand containing the mineral or metal to be separated is fed to the tray B between the water-box H and the end b^2 , falling upon the incline C^2 . Water is at the same time admitted to the box H through the inlet K, and 20 rotary motion communicated to the shaft G, causing the tray B to be reciprocated lengthwise and made to rise and fall elliptically between its shaft-support G and rigid support F. This motion of the tray, combined with the 25 action of the water, has the effect of separating the mineral or metal from the sand, the latter, with the water, passing over the dam C', while the former is worked back over the dam C, and passes down through the opening 30 b^4 to the conduit E, and thence, by an incline, E', to a suitable receiver. The water and sand which pass off through the conduit D may be permitted to flow away or may be caused to drop into another tray, B', similar to that 35 40 which they have just left, there to be treated for any mineral or metal which may possibly have escaped separation in the first operation.

The object of the incline C^2 is to receive the ore fed to the machine and lead it beneath the water-box, and also to prevent the swash which would result from a wave meeting a vertical wall, like the end b^2 , the reciprocation of the tray producing a succession of waves, which gently roll up the incline, and on their 45 recession leave the heavy parts suspended in them on their ascent, or a portion of such parts deposited on said incline.

Under some circumstances the dams C C' 50 55 may be dispensed with, and where slime ore is to be treated the bottom b may be roughened by any suitable means, as by coating said bottom with linseed-oil and putting on over the oil a layer of sand. This coating or roughening (indicated at b^6) has the effect of holding the mineral or metal and earthy matter suspended in the water until separation is effected, where, if a roughened surface were not provided, the slime would sink to and become deposited upon the bottom of the tray, defying 60 separation.

Where ore containing minerals or metals of different specific gravities is to be treated, said minerals or metals may be separated from the sand or earthy matter and from each other by 65 providing as many trays as there are kinds of minerals or metals in such ore, and arranging

the trays one above the other at different angles of inclination with reference to the horizontal bars a^2 . Thus, the uppermost tray should be set at such an angle as that the 70 heaviest mineral or metal will be separated therein from the residue of the ore, which will pass to the tray below, the latter being set at an angle of inclination different from that of the tray above. Here the mineral or metal of 75 the next greatest gravity will be separated, and so on through the series of minerals or metals, until the residuum from the last tray is sand or refuse matters.

The angle of inclination for the tray or trays 80 must be determined by the quality or character of the ore treated under the judgment and skill of the operator. With ore containing four per centum of sulphurets I have obtained complete separation with a tray about five feet 85 long, arranged so that when its eccentric, which had a throw or moved through a circle having a diameter of one inch, was at its top center said tray was horizontal, or nearly so, throughout its entire length, and when said eccentric 90 was at its lower center the adjacent end of said tray was lower than its other or flow-off end.

Any suitable means for adjusting the angle of inclination of the tray which will not interfere with the peculiar manner of its movement 95 may be employed.

The means I have illustrated consist in making the sustaining cross-piece F' movable on the bars a^2 , and sliding it along said bars to or from the shaft G, as the necessities of the 100 case require. When adjusted for a given quality of ore said cross-piece should be firmly fastened in position by screws or other retaining devices until a change of its location is required.

The water-box is made adjustable to different angles, it being important to vary the direction of impingement of the jets of water with ore of different grades.

The angle of inclination of the water-box 110 will depend upon the quality—i. e., fineness or coarseness—of the ore to be treated. I have satisfactorily treated or separated ore so fine as to pass through a screen of a hundred meshes to the inch with the water-box standing at or about the angle indicated in the drawings. With coarser ore the box may be required to be adjusted nearer to or even in a vertical line, or inclining in a direction contrary to that shown in the drawings, or with 115 its discharge-opening toward the base of the incline C^2 .

The original, drawings which are made to a scale of one-half an inch to the foot, indicate the relative sizes of the parts of the apparatus.

In practice I would recommend that the trays be ten feet long and as wide as may be consistent with strength, the other parts being in proportion. With a tray of the dimensions given the water-inlet K may be half an 120 inch in diameter.

To produce the best results attainable with

this separator I recommend that the shaft G be run at a high rate of speed. With ore containing four per centum of mineral and fine enough to pass through a screen having a hundred openings or meshes to the inch I have obtained very thorough separation when the shaft G made four hundred and twenty-five revolutions per minute, the tray, of course, reciprocating correspondingly, and less satisfactory results when the speed was either increased or lessened.

As a substitute for the water-box H, a pipe having a slit-opening or a line of perforations on its under side may be employed.

15 What I claim as my invention is—

1. The combination of the tray B, constructed as described, whereby ore will pass over one end of the same, with a support at one end having a fixed axis, and an eccentric or crank shaft at the other, whereby a longitudinally-reciprocatory movement is imparted to one end of said tray, while an elliptical movement in a vertical plane is imparted to the other end, substantially as described.

25 2. In combination with a separator-tray, B, a pivoted adjustable water-box, H, substantially as shown and described.

3. A separator-tray, B, having transverse cleats or ribs C C', the sides of which adjacent to the water-box are inclined, while their reverse sides are vertical, forming dams, substantially as shown and described.

4. The reciprocating separator-tray B, in combination with an incline, C², at one end, set at an angle to its bottom b, said incline terminating above the bottom, so as to leave a passage-way for the minerals between its lower edge and said bottom, substantially as and for the purpose set forth.

40 5. The separator-tray B, having a sanded or granulated bottom, substantially as described, for the purpose set forth.

6. The combination of tray B, frame F, support or cross-piece F', crank-shaft G, and

water-conductor H, substantially as shown 45 and described.

7. The combination of the tray B with the eccentric or crank shaft G, supporting one end, and with the bar F', supporting the other end, so as to allow the same to be raised and lowered in order to vary the angle of inclination of the tray, substantially as described.

8. In combination with the horizontal bars or supports a², the tray B, cross-piece F', and eccentric or crank shaft G, the several parts 55 being arranged and operating substantially as shown and described.

9. In an ore-separator, the combination of two or more trays supported in a suitable frame with separate and independent eccentric or 60 crank shafts, substantially as shown and described, whereby they are reciprocated longitudinally and moved elliptically at one end in vertical planes, each of said trays being adjustable so as to vary the angles of inclination of their bottoms, said trays being also placed one above the other, and each provided with a water-box and an incline, so as to separate from each other and from the sand or other refuse matter metals or minerals of different specific gravities.

10. In combination with the frame A, supports a², and transverse eccentric or crank shafts G G, the trays B B', placed one above the other, and adapted to move longitudinally and elliptically in vertical planes, each of said trays having water-conductors H H and inclines C², and the upper tray, B, having a conduit, D, leading to the tray below, substantially as shown and described.

In testimony that I claim the foregoing I have hereunto set my hand this 2d day of November, 1877.

WILLIAM L. IMLAY.
